Specification of Letters Patent. Patented Sept. 18, 1917.

Application filed June 13, 1916. Serial No. 103,553.

To all whom it may concern:

Be it known that we, ADRIAN VAN LEEUWEN, Jr., and FRANCOIS X. BRUNELLE, citizens of the United States, both residing at 5 Worcester, in the county of Worcester and State of Massachusetts, have invented a new and useful Furnace, of which the following is a specification.

This invention relates to a furnace for 10 generating steam for power plants and house-heating purposes and also adapted to heat water for hot water heating systems.

The principal objects of the invention are to provide a furnace having a minimum 15 amount of water therein and a maximum heating surface, which can conveniently be made up of sections; to provide a water circulating arch over the fire box to receive the direct heat from the grate and force the 20 smoke and gases back toward the grate before they are allowed to escape; to provide means whereby unconsumed gases from the fire-box can be ignited and burned within the furnace beyond the arch, so as to utilize 25 the full effect thereof; to provide water tubes or passages so arranged as to receive a maximum heating effect; to prevent the escape 30 of large quantities of heat from the outside surfaces; to provide improved means for supplying air for purposes of combustion to the fire-box and to the combustion chamber in which the unconsumed gases from the fire-box are burned, and to provide improvements in the details and arrangements of the 35 several sections for the purpose of increasing the efficiency of this type of furnace, so as to produce full combustion and yet provide a furnace that will not be complicated or expensive to build, set up or keep in order. 40 Reference is to be had to the accompanying drawings in which—

Figure 1 is a front elevation of a steam furnace constructed in accordance with this invention;

Fig. 2 is a longitudinal, central, sectional view on the line 2—2 of Fig. 1;

Fig. 3 is a view taken on the line 3—3 of Fig. 1, and constituting in effect the front elevation of the second section of the furnace, the outer section being removed;

Fig. 4 is a sectional view through the second or intermediate section on the line 4—4 of Fig. 2;

Fig. 5 is a sectional view of the third or

central section on the line 5—5 of Fig. 2, 55 showing the air passages to the upper combustion chamber;

Fig. 6 is another view of the same section on the line 6—5 of Fig. 2, showing the air passage to the fire-box, and 60

Fig. 7 is a sectional view on the line 7—7 of Fig. 1.

Several types of furnaces of the water tube variety for heating water and making steam have been designed for house heating and 65 other purposes. These have proved efficient in practice, but are subject to certain losses, particularly a loss due to the fact that the fuel cannot be entirely consumed in the fire-box, some of the constituents thereof being 70 converted into combustible gases at a point above the fire, from which they escape without their heating properties being utilized. Furthermore, the water tube variety of furnace is expensive, owing to the large quantity of tubing required and the hand work 75 necessary to connect the parts. This invention is designed to retain all the advantages of the water tube type of heater, and to obviate in a very high degree the above mentioned objections. 80

In order to substitute castings for previously formed tubes, the furnace is made up in sections each one being originally cast with spaces therein, constituting in effect 85 tubular water receiving elements, and these are made small enough so that they can be handled conveniently, and set up either at the factory or in the cellar of the house to be heated in a most expeditious manner, so that 90 the cost for labor will be very greatly reduced. In this manner they can be designed without additional expense so as to greatly increase the efficiency by increasing the heating surfaces, surrounding the furnace with 95 water holding walls, and providing a second combustion chamber in which the unconsumed gases can be burned within the furnace thus obtaining full efficiency.

A preferred manner in which these advantages can be secured is indicated in the accompanying drawings which illustrate one embodiment of the invention. In these drawings the furnace is shown as having an ash pit 10 at the bottom, formed of a casting 100 separate from the rest of the furnace, and capable of being handled independently thereof. This is located in the usual way

and supports any desired number of furnace sections. In the drawings we have shown six of these sections, two central sections 11, two intermediate sections 12, and two end sections 13. The two sections of each pair preferably are duplicates of each other substantially.

The end sections differ from each other slightly on account of the furnace door 14 being located in one of them, and not in the other. The door 14, in itself, is of the usual construction, but instead of being supported directly on hinge pins carried by the integral parts of the furnace or furnace sections, it is supported on a hollow plate 16 which is removably mounted on the front of this section, and can be opened if necessary to furnish more complete access to the firebox and other interior parts. This plate 16 of course has an opening back of the door 14, and is supported at its ends by two brackets 17 cast on the furnace section and is held in position thereon by pins 18.

The end sections are both provided with pairs of doors 15 through which access to the upper part of the combustion chamber may be secured for cleaning purposes and the like. The doors 15 are hollow walled, each one being cast with a plane surfaced rib 15^a around it, to which is bolted a flat plate 19. This furnishes an insulating air space which may be filled with insulating material if desired. The plate 16 is made in the same way.

It may be stated at the present time that each of these end sections is formed with a lower hollow water wall 20. In the front section this wall surrounds the bottom of the door. Communicating directly with the ends of this section is a hollow water wall 21 which extends around the exterior at the top and furnishes a free space for the circulation of water. Furthermore these walls 20 and 21 are connected by a hollow water circulating arch 23 over the fire-box which is connected with the outer water wall by a plurality of conduits 22 which preferably are arranged vertically, and provide for the free passage of water between the walls 23 and 21. The opposite surfaces of these sections are shown as lying in a plane. The purposes of these parts are the same as those of the corresponding parts of the intermediate sections 12 and central sections 11, and will be described more fully in connection therewith.

Referring first to the sections 12, shown more fully in Figs. 3 and 4, it will be seen that each one is provided with a lower hollow water chamber 25 extending across each side. These water chambers are connected directly at the bottom by a transverse water wall 25' their upper ends by an exterior full width hollow wall 26 corresponding with the wall 21 in the outside section. A water

wall 25' is located at each end of the furnace and each one extends only about half way across the section 12. Just above the firebox in which the grate is located is an arch-like inner wall 27 for receiving the direct heat of the fire. This is hollow, having a water space 28 connected at both ends with the chambers 25 and 26. The spaces 26 and 28 are connected by a series of conduits 29 which are shown in the drawings as vertically arranged in a plane. The conduits 29, like their counter parts 22, preferably are not circular in cross section but have acute front and rear edges to furnish a large heating surface for a small quantity of water to be heated. They are not as wide as the walls 26 and 27 so as to furnish a vertical open space between each two series of vertical conduits.

All these parts of the section 12 are formed of single casting, and are integral with each other. From this it will be seen that the water surrounds the fire-box at the sides and top, that the water which is closest to it and receives the direct heat has perfect freedom of circulation upwardly through the space 28, and into the space 26, either at the outside or through the conduits 29, and that these parts are so shaped as to provide a maximum heating capacity for a minimum amount of water.

Each section 11 has also a lower arch 27^a (see Fig. 5) having a space 28^a for water, as well as external water walls 26^a and two lower water chambers 25^a. These correspond in a general way with the similarly numbered parts of the sections 12, but the side water chambers 25^a extend clear across the sections 11, and there is no lower connection between them at the bottom.

The parts are assembled in close relation to each other, as indicated, so that the walls 26, 27 and 27^a of the several sections come into contact and constitute a continuous arch over the fire-box from one end of the furnace to the other. A second continuous external water filled arch is formed by the walls 21, 26 and 26^a which forms the external side walls of the furnace. This outer arch being filled with water provides means whereby the furnace is prevented from radiating the usual amount of heat into the air, and an additional means for assisting in heating the water, although the central arch may be considered as forming the main heating portion of the furnace.

The water is introduced into the bottom of the water chambers, and it will be understood that at the bottom and top, are openings 33 at both ends of the inner sections 11, and at one end in the sections 12. They constitute means for conducting water from one section to another, thereby providing the necessary circulation.

The water enters the bottom of one or

both of the water chambers 25 at one end, enters all the sections, passes upwardly through these chambers and the corresponding parts of all the sections and immediately 5 comes into contact with the heated surfaces at the sides of the fire-box. As the hottest part of the furnace is at the top of the arch 27 there will be a tendency for the water to circulate upwardly from this point 10 through the tubes 22, 29, 29^a, if they are full, and if the water in the spaces 21, 26, 26^a has a tendency to become cooler it will be drawn down around the outside and forced upwardly again so that an even uniform 15 temperature will be maintained throughout the water spaces of the furnace.

The sections are assembled simply by securing them together by means of bolts 32 and mounting on the ash pit frame as indicated. 20 These bolts extend through the passages 33. The outside sections can be secured in the same way but are shown as connected by bolts 32^a extending through openings 33^a, one of which is T-shaped. The 25 water or steam may be circulated from the furnace through a pipe 34, as indicated.

The space below the arch 27 is free and open from one end of the furnace to the other, while the space between the arch 27 30 and the outer wall 26 is also free except for the tubes 22 and 29 which assist in utilizing the heat for the heating of the water located in them. The upper surfaces of both arches are corrugated to provide for efficient heating 35 of the water.

An important feature of the invention consists in the provision of means whereby some of the unconsumed products from the fire-box are subjected to a temperature 40 sufficient to ignite them and provide combustion in the upper combustion chamber by the addition of freshly introduced heated air. For this purpose the contacting walls of the lower arch in the sections 11 and 12 45 are provided with semi-circular slots 35 which register with each other to form ignition jet openings. Through these gas escapes in the form of jets into the upper combustion chamber where the mixture of gases 50 and heated air is ignited on account of their high temperature, thereby securing perfect combustion. Four of these are shown in these drawings.

Around the side edges of the arch 27 are 55 smoke flues 30 for conducting the smoke and gases from the fire-box up into the upper combustion chamber and assisting in heating the tubes 29. The jet openings 35 do not let all the gases through freely and the 60 arch forces the remainder back down toward the grate at the sides and up the four flues 30. Thus they are perfectly mixed together and also mixed with the fresh air coming up two air passages 36 at the sides as will appear. 65

The manner in which the external air is brought in to support combustion is also a feature of importance. For this purpose the two sections 11 are provided on their sides adjacent to the sections 12 with an air 70 channel 36 on each side. The sections 12 are also provided on their adjacent inner surfaces with channels 37 which register with these channels 36. These channels 37 extend from below the fire-box up into the 75 sides of the lower combustion chamber, while the channels 36 extend from the same place up into the ends of the upper combustion chamber. They are separated along the sides of the lower arch by the walls 80 thereof, and are further separated by a removable member 38 which is provided with a flange 39 inclosing the open sides of the channels 36 and 37 so as to permit each channel 37 to form an air-conducting conduit from below the fire-box into the top of the lower combustion chamber above the top of this flange 39. The other channel 36 is also closed on the inner side by this flange, the bottom of course being open, forming 90 two separate conduits. This member 38 preferably is removably held in position by means of a stud 40 cast on the wall of the section 11 on which this plate is hinged at its top, and fits on a ledge 41 on the wall of 95 the section 11. To remove it, it is displaced laterally from its stud, and drawn out into the fire-box.

In this way a current of heated air is brought independently into each combustion 100 chamber from below. We prefer to conduct this from below the ash-pit by means of a conduit 42 cast on the wall or otherwise supported at the sides of the member 10, and extending upwardly from a well 43 below 105 the ash-pit which can supply fresh air from any desired source. The supply preferably is controlled by a damper 44.

It will be understood that gases which flow directly upwardly from the grate in 110 contact with the inner surface of the lower arch, are discharged with some force through the ignition jet openings 35, and that the remainder are forced down toward the grate and discharged through the flues 115 30 into the upper combustion chamber. When this arrangement is used for generating steam the water level is kept above the crown of the hollow arch 27.

Although we have illustrated and described only a single form of the invention and shown it as formed of a certain number of sections, we are aware of the fact that many changes can be made in the construction, that other numbers of sections can be 125 used, that the sections need not be vertically arranged and that some of the principles can be carried out without departing from the scope of the invention, as expressed in the claims. 130

Therefore we do not wish to be limited in these respects, but what we do claim is:—

1. A sectional heater comprising a plurality of sections, each provided with an external water wall and a water arch connecting the two sides of the external water wall and providing a combustion chamber between them above the arch, the space below the arch constituting a fire box, the edges of the arches of the several sections coming substantially into contact with each other to make the arch continuous, said sections having a series of substantially continuous and substantially parallel water conduits extending from the arch to the external wall, but spaced from each other to permit circulation of air and gases around them, and means for conducting air into the fire-box and combustion chamber from below the fire box.
2. A sectional heater comprising a plurality of sections, each provided with an external water wall and a substantially horizontal inner water wall or arch connecting the two sides of the external water wall and providing a combustion chamber between them above the arch, the space below the arch constituting a fire box, the edges of the arches of the several sections coming substantially into contact with each other to make the arch continuous, said arch having jet openings therethrough to admit gases from the fire box into said combustion chamber, said sections having substantially vertical continuous water conduits extending from the arch to the external wall, but narrower than the sections and spaced from each other to permit circulation of air and gases around them in all directions, and means for supplying air both above and below the arch to support combustion.
3. A sectional heater comprising a plurality of sections, each provided with an external water wall and a water arch connecting the two sides of the external water wall and providing a combustion chamber between them above the arch, the space below the arch constituting a fire box, the edges of the arches of the several sections coming into contact with each other to make the arch continuous, said sections having substantially continuous water conduits extending from the arch to the external wall, but spaced from each other to permit circulation of air and gases around them, a grate at the bottom of the fire box, and means for conducting air around the fire box to heat it and into the top of the fire box below the arch, the edges of the arch curving downwardly and inwardly at their ends to force the products of combustion back toward the grate.

4. A water heater having an inner and an outer hollow wall for the circulation of water spaced apart to form an upper combustion chamber separated from the fire box

by said inner wall, said inner wall having jet openings passing transversely through the water filled inner wall for admitting the unconsumed gases from the fire-box into the space between said inner and outer walls, 70 and air supply passages into said combustion chamber between said inner and outer walls.

5. A water heater having an inner and an outer wall, said inner wall constituting a 75 substantially continuous flat arch over the fire box and having a plurality of jet openings therethrough for admitting the unconsumed gases from the fire-box into the space between said inner and outer walls, 80 said space being practically as deep as the fire-box, and air supply passages from below the fire-box opening inwardly into the space between said inner and outer walls to supply preheated air to the combustion chamber 85 formed in said space.

6. A furnace comprising sections having an inner and outer hollow wall for the circulation of water, water chambers at the other sides connecting said inner and outer 90 walls, a grate, and air supply passages extending into the space below said inner wall and over the ash pit from below the grate at the inner sides of the water chamber.

7. A furnace having an external wall, an 95 inner hollow arch, water chambers connected with the ends of said arch, and a fire-box between said water chambers and below the arch, said external wall and arch being spaced apart to form a combustion chamber 100 above the arch, and means for conducting air from below the fire box, in contact with its walls so as to heat it, into the space below the arch, and means for conducting air into said combustion chamber.

8. A furnace having a fire-box, a hollow external wall for receiving water extending upwardly therefrom, a hollow arch spaced inside the external wall over the fire-box and adapted to receive water, means inside the 110 external wall for conducting air from below the fire-box into the space below the arch and into the space above the arch, and means for conducting gases from the fire-box into the space above the arch, both through and 115 around the arch.

9. A furnace having a fire-box, a hollow external wall for receiving water extending upwardly therefrom, an arch spaced inside the external wall over the fire-box, means 120 inside the external wall for conducting air from below the fire-box into the space below the arch and into the space above the arch, and means for conducting gases from the fire-box into the space above the arch.

10. A furnace having a fire-box, an external wall extending upwardly therefrom, an arch spaced inside the external wall over the fire-box, means inside the external wall for conducting air from below the fire-box into 130

the space below the arch and into the space above the arch, and means for conducting gases from the fire-box into the space above the arch, both through and around the arch.

5 11. A furnace of a general rectangular form having an arch over the fire-box, water-holding conduits extending upwardly from said arch, smoke flues widely spaced from each other, located at the four corners of the 10 furnace, and leading from the fire-box up into the space above the arch, and a central outlet for the products of combustion, whereby the heated products are forced to pass from the corners inwardly to the center past 15 and around said conduits.

12. A furnace having an external wall, and an arch inclosed within said wall and spaced therefrom, flues located between the arch and external wall and extending into 20 the space above the arch from points at the bottom of the sides of the arch, the side edges of the flues extending toward the fire-box to force the gases back toward the grate before discharging them above the arch.

25 13. A furnace having an external wall, and an arch inclosed within said wall, flues extending into the space above the arch from points at the bottom of the arch, the side

edges of the flues extending down toward the fire-box to force the gases back toward 30 the grate, and means for introducing air to support combustion above the arch.

14. A furnace having external water walls provided with a front opening, a double walled plate removably mounted to cover 35 said opening, said plate having an opening, and a double walled door covering the last named opening.

15. In a furnace, the combination with a wall thereof having an upwardly extending 40 air conducting channel, and a readily detachable member supported by said wall and forming the inner wall of said channel to separate it from the fire-box.

16. In a furnace, the combination with a 45 wall thereof having an air channel, and a member of T-shaped cross section extending into said channel and dividing it into two and covering the channel on its inner side, said member being detachably pivoted to the 50 wall.

In testimony whereof we have hereunto affixed our signatures.

ADRIAN VAN LEEUWEN, JR.
